UNITED STATES PATENT OFFICE.

WILLIAM ALONZO BRAMBERRY, OF NORFOLK, VIRGINIA.

SELF-LOCKING SEAL.

1,123,838.

Specification of Letters Patent.

Patented Jan. 5, 1915.

Application filed February 13, 1914. Serial No. 818,511.

To all whom it may concern:

Be it known that I, WILLIAM ALONZO BRAMBERRY, a citizen of the United States, residing at Norfolk, in the county of Norfolk and State of Virginia, have invented certain new and useful Improvements in Self-Locking Seals, (Case B;) and I do hereby declare the following to be a full, clear, and exact description of the invention, such as will enable others skilled in the art to which it appertains to make and use the same.

My present invention relates to improvements in self-locking seals, and it is especially intended to provide a cheap and simple seal for railway cars which may be readily attached, and broken when it is desired to remove same, but which cannot be tampered with, without showing the result of such tampering.

While the invention is especially intended for use in sealing up freight cars on railroads, it may be applied to sealing up any wagon, package, or other article, where it is desired to keep the same unopened, and to attract the attention of inspectors when the seal has been tampered with.

My invention is especially intended to provide certain improvements on the seal shown in my Patent No. 1038485, granted September 10, 1912 and entitled improvements in self-locking seals.

My invention will be understood by reference to the accompanying drawings, in which the same parts are indicated by the same reference symbols throughout the several views.

Figure 1 is a plan view of the metal blank before it is bent up to form a complete seal, and showing the said blank in the flat condition; Fig. 2 is a central section along the line 2—2 of Fig. 1, looking in the direction of the arrows, but showing the strip bent up to form the seal; Fig. 3 shows the complete seal in the final position as in ordinary use; Fig. 4 is a detail showing one end of the seal before the bending has been completed; Fig. 5 is a perspective view showing the other end of the seal from that shown in Fig. 4; Fig. 6 is a similar view to Fig. 2, showing the interlocking ends of the seal in the locked position; and Fig. 7 shows a modification in which there is an additional depression and locking lug.

Referring first to Figs. 1-6, 1 represents

a blank of sheet metal, preferably tin, or the like, which is provided with notched portions 17 for convenience in bending, and notched portions having deeper notches 3 and 16 to weaken the seal so as to provide a position line of fracture close up to the box end, should the seal be tampered with by breaking and attempting to reinsert either end in the box. By providing these notched portions, making the breaking point of either end of the strap 1 close up to the boxed end, this leaves no shelf or holding for the broken strap. One end of this blank is reduced in diameter and slotted as at O to form two tongues 4, which are bent over to provide the locking hooks 5, the bend being along the line 6—6 of Fig. 1. The plate is provided with beveled notches 7, not only for convenience of locating the proper line 6—6 for bending; but mainly to provide a tapered throat to serve as a guide for the insertion of the tongue 11 in the slot O, and thus facilitates the locking of the seal. The other end of the blank 1 terminates in a hook 9, which is bent over along the line 10—10 adjacent to the part 8, and this hook 9 is provided with an ear 11, which projects down into the recess 13 in the body of the plate; the part 8 being bent over along the line 12—12, and the sides 14 and 15 being bent in to form a box at the rear end of the blank, as shown in Fig. 2. This ear 11 projecting into the recess 13, the sides of the box being closed and fastened together, will lock the tongue 9 against being withdrawn should any one attempt to violate the seal by cutting along the line 10—10, when the seal is locked. The seal being bent in the manner shown in Fig. 2, in order to lock the same the free end is turned upward, and the two hooks 5 are slipped into the box, the slot O, and the beveled notches 7, permitting the easy guiding of the tongues 4 into said box and past the ear 11. The seal is shown in the locked position in Figs. 3 and 6.

In the modification shown in Fig. 7, I provide a boss 20 stamped out of one side of the plate, adapted to fit in a recess 21 when the plate is in the folded-over locked position. These furnish an additional holding means when the seal is applied; also provide for a position line of fracture along the line 3—3 or 16—16, and the bosses 20 and 21 being pressed up in the opposite direction

from the recess 13, when the seal is in use, serve as an additional means to prevent the insertion of the fore end of the strip into the box when the seal is broken, thus preventing the concealment of the ruptured condition of the strip.

It will be noted that I provide a closed box at one end of the seal, which cannot be tampered with by inserting tools from the side thereof, and into this box the free end of the blank slips, causing the hooks 5 and 9 to interlock, and rendering it impossible to disengage the same without breaking the seal. Moreover when the seal is broken, it will be impossible to insert the free end of the broken part into the box, and thus conceal the fact that the seal has been broken. While I preferably provide a recess 13 for the ear 11, it will be obvious that such recess 20 may be dispensed with if desired.

It will be obvious that various modifications might be made in the herein described seal, and the construction, combination and arrangement of parts which could be used 25 without departing from the spirit of my invention.

Having thus described my invention, what I claim and desire to secure by Letters Patent of the United States is:—

30 1. A locking seal comprising a blank strip of metal constructed at one end to provide a closed box, one wall of said box having an ear provided with a curved outer edge projecting downward into the interior thereof, 35 with a curved indentation in the opposite wall of said box adapted to receive said ear, one end of said blank being bent into said box to form an engaging hook therein, and the opposite end of said blank being slotted, 40 and provided with engaging hooks adapted to slip into said box past said ear, and to engage the hook in the box, substantially as described.

45 2. A locking seal comprising a blank strip of metal constructed at one end to provide a closed box, one wall of said box having an

ear projecting downward into the interior thereof, with a recess in the opposite wall of said box adapted to receive said ear, one end of said blank being bent into said box to 50 form an engaging hook therein, and the opposite end of said blank being slotted longitudinally with a beveled throat at the outer end of the slot, and provided with engaging hooks adapted to slip into said box 55 past said ear, and to engage the hook in the box, substantially as described.

3. A locking seal comprising a blank strip of metal constructed at one end to provide a closed box, one wall of said box having an 60 ear projecting downward into the interior thereof, one end of said blank being bent into said box to form an engaging hook therein, and the opposite end of said blank being slotted longitudinally with a beveled 65 throat at the outer end of the slot, and provided with engaging hooks adapted to slip into said box past said ear, and to engage the hook in the box, substantially as described.

70 4. A locking seal comprising a blank strip of metal constructed at one end to provide a closed box, one wall of said box having an ear projecting downward into the interior thereof, with a recess in the opposite wall of 75 said box adapted to receive said ear, one end of said blank being bent into said box to form an engaging hook therein, and the opposite end of said blank being slotted and provided with engaging hooks adapted to 80 slip into said box past said ear, and to engage the hook in the box, the said strip having a recess therein, and a boss thereon engaging said recess, said recess and boss being exterior to said closed box.

85 In testimony whereof, I affix my signature, in presence of two witnesses.

WILLIAM ALONZO BRAMBERY.
